AUGUST ABEL, OF LEIPZIG, GERMANY, ASSIGNOR TO THE FIRM: ATLAS-WERKE
PÖHLER & CO., OF LEIPZIG-SLOTTERITZ, GERMANY

SHOEMAKING MACHINE

Application filed January 21, 1927, Serial No. 162,635, and in Germany January 21, 1926.

This invention relates to machines for manufacturing boots and shoes and more particularly to that class of machines in which the shoe or workpiece is held by a workman controlling the machine operation so that the various mechanisms thereof may in due succession and at proper times perform their intended functions on the workpiece.

10 A typical example of this kind of shoemaking machine is the hand-method lasting machine, embodying a gripper for pulling the uppers over the lasts, a distributor for supplying tacks of different sizes, a hammering device for hammering the tacks through the pulled-over portions of the upper into the last, a combined tack change-slide and movable work-rest, and a slitting device, all of which mechanisms are brought 15 into operation by an attendant controlling the same by hand or foot movement as required.

This invention aims to render such machines self-controlling and to thereby increase 20 their working speed and efficiency. According to the invention, the workman is relieved of strenuous hand and foot operations and need merely hold and guide the workpiece, while the machine will automatically bring 25 its various working mechanisms into play in proper sequence and at the correct moments.

In carrying out the invention, means such as special control discs are provided to cause 30 an intermittent functioning of the machine from a continuously rotating drive shaft in such manner that the machine will be stopped and restarted synchronously with the workman's progress in guiding the workpiece and 35 changing its position. Thus, the times or stages of automatic stopping of the machine are made to correspond with the time required 40 for the workman to turn the workpiece, say from one side to the other, a comparatively long stop being effected at the 45 conclusion of a complete operative cycle to permit the workman to lay aside the finished workpiece and to take up a new one, while the duration of periods of successive 50 steps or work operations are made to corre-

spond with the time required to complete each of such steps through the complete cycle of operations. Accordingly, a working period during which seven tacks are to be applied will be longer than one in which only 55 five tacks are to be hammered into place.

In addition to the above mentioned means, means such as cams, gears, lever arrangements and the like are provided to bring each of the various working mechanisms into play 60 at the proper time, provision also being made for counting and recording the number of working cycles performed, for increasing or decreasing the working speed and for setting all automatic driving and controlling 65 means into inoperative relation, the last-mentioned provision being desirable, for example, when particularly difficult work is to be carried out.

The invention will be best understood by 70 reference to the accompanying drawings wherein one form of automatic drive and governing means embodying the same is illustrated for example in application to a shoe-lasting machine.

In said drawings:

Fig. 1 is a side elevation of a lasting machine equipped with means embodying this invention, certain parts being shown in section;

Fig. 2 is a diagrammatic representation of one form of means provided for effecting an intermittent automatic drive of the machine;

Fig. 3 is a side elevation of a clutch detail 85 for said machine;

Fig. 4 is a section through the change-speed gearing, taken on the line IV—IV of Fig. 2;

Fig. 5 is an elevation in illustration of a 90 structural detail; and

Fig. 6 illustrates a combined work rest and tack-slide shifting arrangement.

The machine represented in Fig. 1 is of the character and type heretofore used under 95 manual control by hand or foot, but which has been modified according to the invention so as to be automatically controlled in the manner hereinafter described.

The numeral 1 denotes the head-piece of 100

the machine which in its upper part carries a main shaft 2 from which the various "work" or step-by-step operations of the machine are initiated. Said shaft is driven intermittently by a pulley 3 through an intermittently engaging clutch mechanism, while said pulley is operable continuously by a belt (not shown) from the counter shaft 5, the latter being journaled in the machine standard 4. The belt pulley 3 is loose on the shaft 2 but connected with a clutch member 6 and also continuously drives a bevel wheel 7 which is in constant mesh with a like wheel 9 carried on the vertical shaft 8.

Said shaft 8 is in turn adapted to drive a worm wheel 10 by means of a worm 11, which latter is carried either on the lower extended end of the shaft 8, as shown in Fig. 1, or on the end of an auxiliary shaft 8^a in which latter case said wheel would be placed in line with the shaft 8^a instead of the shaft 8, as shown in Fig. 2. This drive is preferably effected as shown in Fig. 2 through a change-speed gearing interposed between the aforesaid bevel wheel 9 and the worm 10, and this preferred drive will be more particularly referred to hereinafter.

The worm wheel 10 drives a cam shaft 12 upon which is keyed a control disc 13 for the control of the various work-operations and intervals thereof. In the example shown, this control disc 13 is constructed with radially disposed cam surfaces, each of which corresponds to and governs the period of one particular operation on the work-piece or shoe. In an operation for example, where tacks are to be inserted through different parts of the shoe (i. e. the toe, left side, right side, etc.), said cam surfaces will accordingly regulate the exact number of tacks to be supplied during the shaft operation period for hammering into the parts of a shoe into which they are respectively intended to go, the feed of the tacks to position before the hammer taking place automatically in the usual manner. The depressions 14 in said disc 13 between adjacent cam surfaces are of such extent as to regulate the desired intervals between successive or each two work-operations, during which the workman may turn or otherwise re-arrange the workpiece or shoe for treatment upon another portion thereof. A longer depression 15 causing a longer interval is provided in the disc at the point of ending a complete rotation, during which longer interval the workman may remove the finished shoe and take up another one for like treatment, by which time the first cam surface of the disc has moved to position effecting automatic operation beginning on a new cycle.

The intermittent drive of the main shaft 2 for periods thus governed according to the steps or partial working operations to be performed takes place by the following

means: Mounted on the shaft 2 is shown a clutch member 16 having a bore open toward the belt pulley, in which a spring-pressed clutch bolt or pin 17 is arranged. A guide-pin 19 projects from the aforesaid bolt through a slot 18 in the clutch-member 16. Normally, the clutch connecting bolt 17 engages with one of a series of holes 20 in the continuously rotating loose clutch-member 6 and in this way causes the shaft 2 to rotate also. In the intervals between successive or each two partial work-operations, and at the end of a complete working cycle, the machine is temporarily declutched. This de-clutching is effected by the guide-pin 19 on the clutch bolt 17 being engaged or tripped by the inclined surface portion 21 of a trip-cam 22, which latter is moved into the path of said pin under control of the rotating cam 13. The pin 19 thus tripped and forced to slide along said surface will move the bolt 17 against the action of its spring and withdraw the bolt from its hole 20 in the member 6, thereby disconnecting the clutch members.

The manner of operating the trip-cam 22 with its inclined surface 21 in relation to the pin 19 for clutching or coupling and declutching or uncoupling the machine in a predetermined succession and with intervals of varying duration will be understood by reference to Fig. 2. The several aforementioned cam surfaces of the control disc 13 are therein designated A, B, C, D, E, and F. As said disc rotates, these cam surfaces respectively raise and lower a working lever 23 having an idling cam roller bearing or resting upon the disc. Said working lever is pivoted at 24 to the machine frame and is shown connected to the aforesaid clutch-operating trip-cam 22 by means of a rod 25, while a spring 26 is shown serving to hold the lever in contact with the control disc 13.

As hereinbefore stated, each of the cam surfaces of the disc 13 corresponds to one particular partial operation of the machine, the length thereof respectively governing or regulating the number of tacks, staples or the like to be applied and hammered into the work-piece. Assuming, for example that the cam surface A corresponds to that period in which the left side of a shoe is to receive six tacks for instance, and that the cam surface B corresponds to the period in which the right side is also to receive six tacks, the depression 14 between the cams A and B is required to stop the machine and allow the workman time within which to turn the shoe for operation on its other side. Cam C may then correspond to the operation of tacking the heel portion of the shoe on one side with seven tacks for instance, and so on through the series in a cycle of disc revolution until with the functioning of cam F, the last partial operation has been finished.

In Fig. 2, said parts of the machine are

shown in position just prior to completion of a cycle of disc revolution. From this figure it will be seen that the roller of lever 23 rests upon the cam portion F and that the trip-cam 22 is held by the rod 25 with its inclined surface portion 21 out of the path of the guide-pin 19. Upon further rotation of the disc 13, the roller on the lever 23 following the periphery thereof will descend into the first interval depression 15 and permit said lever to drop under the action of the spring 26, thereby pulling the rod 25 downwardly and moving the trip-cam 22 with its inclined surface portion 21 into the path of the pin 19 on clutch-bolt 17, whereupon said pin 19 will be pressed along the incline 21 and cause the bolt 17 to be retracted and withdrawn from engagement in the hole 20 of the clutch member 6. Premature release-
ment of the bolt 17 for re-engagement with one of the holes 20 is prevented by the pin 19 being pressed against a projection 27 of trip-cam 22 by which it is held until the trip-cam 22 is again swung with its inclined surface 21 out of engagement therewith. This will follow after the proper interval when the roller on the lever 23 rises over the next suc-
ceeding cam surface A to lift the lever 23 as the disc 13 rotates. At this moment the pin 19 is instantly released and the bolt 17 will freely enter one of the holes 20 in the clutch member 6, thus causing the first or next partial operation to begin and take place. The aforescribed locking position of the trip-cam 22 with the pin 19 is represented in dotted lines in Fig. 2.

While the lever 23 is actuated by the control disc 13 for the main purpose of effecting a coupling and uncoupling of the main shaft 2 in the manner described, it may advantageously be used also to actuate a ratchet wheel 29 of an indicating device by means of a pawl 28 carried on its free end. Said ratchet wheel is shown connected to the shaft 30 of an indicator disc and is moved clockwise by the pawl 28 to the extent of one tooth upon each drop-movement of the lever 23. The indicator disc is arranged within a casing 31 having an opening 32 through which the progress of the work of the machine may be indicated. The advance of the indicator disc to the extent of one tooth of the ratchet wheel 29 as described, is effected at the end of each partial operation in preference to the beginning of such operation, so that the intervals between will always be indicative of the partial operation next to follow.

Said indicator may be connected with a total revolution mechanism and indicator 33 of any known type for registering the total number of revolutions made by the indicator disc, thus keeping accurate record of the gross output of the machine, since the ratchet wheel 29 makes one revolution with every complete cycle revolution of the control disc 13.

While the described arrangement of functioning parts produces an automatic intermittent drive for the machine, it is nevertheless possible to throw such parts out of operative relation and employ only the main drive as hereinafter described, the various partial operations of the machine being then controlled as heretofore by the hand or foot. The manner in which this may be effected will be described hereinafter. Such way of working may be desirable in some cases where particularly delicate or difficult work is to be done, and the workman must proceed with greater deliberation and care than would be permissible with the automatic control of the ma-
chine.

In the illustrative machine of Fig. 1, the work-rest 34 and the tack-slide 35 are connected so that the operation of one will cause simultaneous actuation of the other as shown more clearly in the detailed view of Fig. 6. The tack-slide 35 is provided with a short rack 92 which is in engagement with a toothed segment 93 adapted to turn with its pin 94 and, by means of a lever 95 and link 96, to move either of the tack supply channels 41 and 42 into working position with respect to the tack-slide 35. This arrangement is known, but according to the invention the hand control usually employed is replaced by an automatic arrangement. Said slide 35 is provided at its lower side with a lug having an eye through which a pin 36 is extended to engage one end of a bar 37. The other end of said bar is connected to a link 39 having a cam roller 38 guided in the groove of a cam 40 on the shaft 12 by which the said link is given a partial swinging movement. By means of this arrangement, the connected slide 35 and work-rest 34 (Fig. 6) are moved to and from the cam 40 in such manner that according to the requirements of work, tacks of the correct size are always fed to the hammer device, such tacks being passed through either of the supply channels 41 or 42 according to the position of the slide 35, while the work-rest 34 takes a position more or less close to the workpiece.

Another grooved cam 44 is shown provided on the shaft 12 to serve for controlling the turning movement of the gripper 43. Said cam acts upon a pivoted link 46 having a cam roller 45 guided in its groove, the said link being connected through a rod 47 with a lever 48 having actuating connection with a twist-
er-sleeve 49 slidable in the usual manner on the shaft of a coupling or mechanism 50 for turning or swinging the gripper 43 at the proper moment into correct position for plaiting the upper.

When working on the toe of a shoe, it is customary to slit the leather of the upper by means of the knives 51 while pulling the upper over the last so as to prevent bulging, to which end said knives are moved into and out

of operative position by means of a link and lever arrangement 53 which is controlled from the shaft 54. In prior art practice, said shaft has been turned by hand, but according to this invention, it is turned automatically at the proper moment under the control of a cam 55 arranged on the shaft 12 adjacent the disc 13. In this instance, the cam 55 is shown integral with the disc 13, but it may be a separate member if so desired. Said cam acts upon a bell-crank lever 57 which is pivoted at 56 and carries a projecting stud guided in a groove of the cam (see Fig. 2). The action of the cam on said lever is such as to cause the latter to work whenever the toe or heel portion of a shoe comes around to place, because it is at this moment that the cutting device should be set in operation. When the toe or heel portion of the shoe has been provided with the correct number of tacks, the cutting device becomes inoperative again by the action of the same cam 55. This operation has heretofore been manually controlled by means of a handle 58 on the shaft 59.

The aforesaid bell-crank lever 57 is provided with a toothed segment 60 on its free end adapted to engage with a pinion 61. The comparatively short stroke of this segment is augmented to the extent required in turning the shaft 59 by means of intermediate gears 62 and 62^a. The last gear in the train imparts partial rotation to a bevel-gear 63 which communicates a like movement to the bevel gears 65 and 66 on a shaft 64. The gear 66 meshes with another bevel gear 67 on the shaft 59 which controls the cutting device, so that whenever the toothed segment 57 is actuated, the shaft 59 is rocked and thereby renders the cutting device operative or inoperative as required.

The bevel gear 66 is mounted on the shaft 64 in contact with an underlying bushing 68 having threaded engagement with the bracket 69 permitting it to be screwed up and down therein. If it is desired to dispense with the automatic actuation of the shaft 59 and to move the shifting device manually into operation by the lever 58, the bushing 68 is screwed down and the gear 66 will drop with said bushing so as to disengage it from the gear 67. The shaft 59 is then free to be turned by hand as required.

Different kinds or sizes of boots and shoes require the supply of different numbers of tacks in each of the partial working operations. According to the invention, the number of tacks supplied during the cycle period therefor may be changed by substituting cams of different surface extents for the controlling cams 13 and 55 or others, care being taken that the length of the intervals between the various partial operations remain the same as before, since these intervals represent the amount of time required by the

workman for handling the work during such intervals. The time between successive strokes of the hammer being constant, it is permissible to alter only the times during which the various partial operations are to be carried out. In other words, each particular partial operation becomes longer or shorter depending upon the number of tacks to be used, while the intervals between such operations remain the same.

As the speed of the main-shaft 2 remains constant, the invention provides an arrangement of variable speed gearing 70 between said shaft and the control shaft 12 as hereinbefore mentioned, in order to avoid the necessity of exchanging the various bevel or worm gears effecting the automatic drive as would otherwise be the case whenever it is intended to vary the working speed of the machine. In the example shown in Fig. 2, three different speeds are represented by the gears 71, 72 and 73 arranged on and rotating with the vertical shaft 8, any one of which gears may be brought into mesh with a gear 76 on shaft 8^a (Fig. 4) by means of an intermediate pinion 75 on the end of an arm 75'. The said pinion is in constant engagement with the gear 76 and adapted to be swung in and out of engagement with said gears and also raised and lowered by a hand-lever 74 extending through an opening 70' in the gear box 70. A spring-controlled lock-pin 77 is provided to hold said hand-lever in the desired position (see Fig. 4), the said pin thereby entering into recesses 77' adjacent the opening 70'. If the hand-lever 74 is moved to the position indicated by dotted lines in Fig. 4, the pinion 75 will be thrown out of engagement with any of the gears 71, 72 and 73 and thus break the driving connection between the two shafts 8 and 8^a, so that the shaft 12 will no longer be rotated.

Thus, when it is desired to vary the working speed of the machine, by taking the drive through the gear 72 instead of 71, for example, as shown in Fig. 2, the lever 74 is first swung into the dotted line position of Fig. 4, thereby swinging the pinion 75 out of engagement with the wheel 71, whereupon the lever is lifted with the gear 76 and swung backward again to full line position with its pinion 75 now engaging with the gear 72, where it is locked with its pin 77 in one of the recesses 77'. However, when the automatic drive is to be disconnected altogether, the hand lever 74 need only be swung out to the dotted line position shown in Fig. 4.

The automatic drive of the machine being thus interrupted, it may then be controlled by hand, which in some instances may be desirable as hereinbefore stated, especially when difficult or delicate work on the shoe is to be done. The control shaft 12 being brought to rest, the main shaft 2 will continue to rotate

and actuate the various working mechanisms of the machine in the usual manner. However, disconnection of the automatic control shaft 12 calls for a disconnection also of the subsidiary controlling devices which are then replaced by the usual hand or foot controlling levers.

These alterations may be effected in a very simple manner. For manual actuation of the gripper 43 for example, there would be required only a lever 79 connected with the lever 48 and a bar 80 connecting the first mentioned lever with a treadle 81 operable against the tension of a spring 82, such parts being represented in broken lines in Fig. 1. The bar 47, in this case, must of course be disconnected from the lever 48 and removed so as not to interfere with the treadle operation. In said figure also, a trigger-shaped lever 83 is shown for the manual actuation of the work-rest 34. In this case the removal of the bar 37 becomes necessary.

In order to keep the two parts 6 and 16 of the clutch in engagement after the control shaft 12 has been disconnected by moving the hand-lever 74 to the dotted line position indicated in Fig. 4, the control-lever 23 may be connected to a bell-crank lever arrangement 84 represented in dotted lines in Fig. 2, said lever being pressed upwards by means of a hand or foot lever (not shown) so that the clutch may be operated as desired. As manual operation of the lever 23 may be obstructed by reason of its roller resting upon one of the cam surfaces of the disc 13, the connecting rod 25 is shown made in two parts connected by a turn-buckle 85 permitting a shortening of the rod to raise said lever out of contact with said disc.

A machine embodying the features of the invention herein described and claimed may be run according to either of the following modes of operation; viz:

1st. Automatic drive of the machine with automatic control of the partial work operations.

2nd. Automatic drive of the machine with manual control of the partial work operations, such as shown in Fig. 1 to be governed by the cams 40, 44 and 55.

3rd. Manual controlled drive of the machine with manual control also of the partial work operations by disconnecting shaft 12 from the main shaft 2 and using the machine like any ordinary hand-method lasting machine.

Since the length of the cam surfaces on the control disc 13 govern the number of tacks supplied and inserted during each of the partial work operations on a shoe, and as these surfaces must be made different for every desired variation in the number of tacks supplied, the invention provides an arrangement by which such variations may be effected quickly and without necessitating

a dismantling of the controlling elements and their bearings.

According to the detail of invention shown in Fig. 5, the different controlling cams need not be formed as integral elements, but may be formed in two parts embodying a base or carrier plate portion 86 which is fixable to the actuating shaft, and separable portions or segments 87 and 88 which are formed with properly related cam surfaces thereon, adapted to be fastened onto said base or carrier plate by means of screws 89 or otherwise. When control cams such as on the disc 13 are to be exchanged or altered, it is necessary merely to detach the segments 87, 88 and to replace them with other segments having the desired cam surfaces. This can be done without a prolonged interruption of work. In Fig. 2 the cam disc 13 is shown formed in a slightly different way, the two cam segments in this instance being applied to the side of the carrier-plate rather than to its periphery.

It is to be understood that the invention is intended to provide an automatic intermittent operation of a shoe machine at a speed which is set by the machine itself, for governed periods according to the time required for the several partial steps or operations of work to be performed and also to provide for manual operations by an attendant on occasions when the allotted intervals of automatic operation are insufficient for difficult or delicate work requiring more or particular care, or when the nature of the work does not permit of its being performed in definitely measured or timed steps, but requires a certain amount of deliberation on the part of the operator, as may be the case for instance with particularly heavy footwear or when using especially tough or hard materials. With this purpose in view, it is not intended that the invention shall be restricted to the example of machine shown and described, as it is obvious that it may be applied to other shoe-making machines without substantial modification, and that the arrangement and configuration of the several parts may also be varied according to requirements, without departing from the spirit and scope of the appended claims.

What I claim is:—

1. In combination with a shoe making machine embodying a working shaft for positively actuating the working mechanisms thereof, a clutch member on said working shaft, a rotating control shaft continuously operated by said clutch member, a control disk on said control shaft, means arranged between said control disk and said clutch member for automatically and intermittently engaging the clutch to cause rotation of the working shaft so as to perform a plurality of successive partial operations on a shoe during each rotation of the control disk, and

- auxiliary control disks on said control shaft having associated means for causing the individual working mechanisms of the machine to be moved into and out of working positions in consonance with the work being performed.
2. In a shoe-making machine having a working shaft for actuating the working mechanisms thereof, a clutch-member on said working shaft, a rotating control shaft operable continuously from said clutch-member, a control disk on said control shaft having a cam surface with a plurality of spaced raised portions of variable extents, means operable by said disk for automatically and intermittently engaging the clutch to cause rotation of the working shaft so as to perform a plurality of successive work operations of predetermined duration depending upon the extents of the raised portions of the cam surfaces of said disk during each rotation of the latter, a slitting device for working on the toes and heels of shoes to be lasted, a cam on the control shaft and means operable by said cam for automatically moving the slitting device into operative position at the proper moment and intervals.
3. In a shoe-making machine having a working shaft for actuating the working mechanisms thereof, means automatically effecting intermittent operation of the machine according to successive stages of work to be performed on the shoe, comprising in combination a rotatably driven member loosely mounted on said working shaft, a clutch element keyed to said shaft and releasably engagable with said member, a control shaft continuously rotated by the driven member and having associated means for changing the speed of the shaft, a disk on said control shaft having a cam surface with a plurality of spaced raised portions of variable extents, means operable by said disk for engaging the clutch with said driven member at predetermined intervals in a cycle of the control shaft's rotation so as to cause intermittent rotation of the working shaft in a plurality of successive work operations of predetermined duration depending upon the extents of the raised portions of the cam surface of said disk, a turnable gripper for gripping and pulling or plaiting the shoe upper, a cam on the control shaft, and associated link and lever arrangement operable by said cam for automatically turning and swinging the gripper into position for operating on the shoe under treatment.
4. In a shoe-making machine having a

working shaft for actuating the working mechanisms thereof, a clutch-member on said working shaft, a rotating control shaft operable continuously from said clutch-member, a control disk on said control shaft having a cam surface with a plurality of spaced raised portions of variable extents, means operable by said disk for automatically and intermittently engaging the clutch to cause rotation of the working shaft so as to perform a plurality of successive work operations of predetermined duration depending upon the extents of the raised portions of the cam surfaces of said disk during each rotation of the latter, a slitting device for working on the toes and heels of shoes to be lasted, a cam on the control shaft and means operable by said cam for automatically moving the slitting device into operative position at the proper moment and intervals.

5. In a shoe-making machine having a working shaft for actuating the working mechanisms thereof, a driven clutch-member on said shaft, a rotating control shaft continuously operated from said clutch-member at variable speed, a control disk on said control shaft, means arranged between said control disk and said clutch-member for automatically and intermittently engaging the clutch to impart rotation to the working shaft so as to perform a plurality of successive partial operations on a shoe during each rotative cycle of the control disk, a slitting device, a shaft for moving said slitting device into operative position, a cam on the control shaft, a bell-crank lever having one arm connected with said cam and its other arm provided with a toothed segment, a bevel wheel rocked by said segment, and a gear arrangement between said bevel gear and said shaft of the slitting device for actuating the same to move said device into position at the proper moments.

6. In a shoe-making machine having a working shaft for actuating the working mechanisms thereof, a driven clutch-member on said shaft, a rotating control shaft continuously operated from said clutch-member at variable speed, a control disk on said control shaft having a cam surface with a plurality of spaced raised portions of variable extents, means operable by the cam surface of said disk for automatically and intermittently engaging the clutch to impart rotation to the working shaft so as to perform a plurality of successive work operations of predetermined duration depending upon the extents of the raised portions of the cam surface of said disk in a cycle of the latter's rotation, a slitting device, a shaft for moving said slitting device into operative position, a cam on the control shaft adapted to determine the time of functioning of the slitting device, a bell-crank lever moved by said cam and provided with a toothed segment,

and a gear arrangement between said segment and said shaft of the slitting device, including a shaft and bevel wheel and bushing having an external thread adapted to be screwed up and down in its bearing and to support the bevel wheel so that the latter follows its movement to move in and out of engagement with its coacting bevel wheel.

7. In combination with a shoe-making machine having a working shaft and a power-driven shaft, means for automatically and intermittently driving the machine; said means comprising a driven element loosely mounted on said working shaft and continuously driven by said power-driven shaft, clutch means releasably engageable with said driven element to cause the latter to rotate said working shaft, a control shaft, means including transmission and change-speed gears arranged between said driven element and said control shaft for continuously imparting rotation from the former to the latter at different speeds according to work requirements, means including a cam element on the control shaft operating a trip-cam member on the clutch means through a cam-operated member and a link connection for intermittently engaging said clutch with said driven element to effect a plurality of partial work operations of the machine in a single cycle of control shaft rotation for periods successively determined by the form of cam surface of the aforesaid cam element, and means operated by said cam-operated member for operating a device indicating the successive work operations of the machine.

In testimony whereof I affix my signature.
AUGUST ABEL.
